CONSTRUCTION FOR DOUBLE-WALLED
TANK CARSOdd A. Hansen, Kenmore, N. Y., assignor to The
Linde Air Products Company, New York, N. Y.,
a corporation of Ohio

Application August 19, 1939, Serial No. 290,970

8 Claims. (Cl. 105—358)

This invention relates to constructions for double-walled tank cars adapted for storing and/or transporting liquefied gases of the kind having relatively low boiling points at atmospheric pressure, and particularly to double-walled tank cars which have the space intervening between the inner and outer cylindrical vessels filled with a powdered insulating material, the space being preferably evacuated to increase the insulating efficiency.

The invention has for its object generally the provision of a double-walled tank car construction in which the component vessels or containers are each separately supported on the car frame at points imposing relatively little stress upon the walls of the vessels.

More specifically, an object of the invention is to provide an arrangement for supporting the cylindrical double-walled container of tank cars of the character indicated with means including an externally associated frame for supporting the double-walled container on the car frame at desired points along the frame where the concentration of stress may be reduced to as low values as are practical.

Another object is to provide means for securing the double-walled container directly to the car frame and brace it against end thrusts in a manner that avoids substantially any liability to apply concentrated stresses to the wall of the outer vessel and which might tend to impair the vacuum where evacuation of the space between the walls of component vessels is employed.

Other objects of the invention will in part be obvious and will in part appear hereinafter.

The invention accordingly comprises the features of construction, combination of elements and arrangement of parts, which will be exemplified in the construction hereinafter set forth and the scope of the invention will be indicated in the claims.

For a fuller understanding of the nature and objects of the invention, reference should be had to the following detailed description taken in connection with the accompanying drawings, in which:

Fig. 1 is a view of a construction for a double-walled tank car shown partly in elevation and partly in vertical section (the section being at right angles to the longitudinal axis of the car), the tank on the car being adapted to have an evacuated insulating space and suitable for storing and/or transporting liquid oxygen in accordance with the invention;

Fig. 2 is a fragmentary sectional view taken on

the line 2—2 in Fig. 1, and shows details in the construction here employed;

Fig. 3 is a detailed view on a somewhat enlarged scale showing the manner of actuating and protecting the controlling means which regulates the passage of liquid to and from the inner vessel;

Fig. 4 is a fragmentary sectional view taken on the line 4—4 of Fig. 1, showing further details of the supporting means here employed.

Referring now to the drawings, and particularly to Fig. 1, 10 denotes a supporting frame externally associated with the container, and from which a wall 11 of an inner vessel of the container is suspended, such vessel being adapted to hold the liquefied gas that is to be placed or stored in the tank car either with or without the aid of a lining or basket (not shown). Outside of the vessel 11 and spaced therefrom is a second or outer vessel 12 which is also suspended from the frame 10, the manner of suspension being herein-after more fully explained. The space intervening between the vessels thus provided is a closed space and has no communication with the outside except that which may be provided through an evacuating connection, when a vacuum is to be employed. The wall of the outer vessel is also preferably strengthened by one or more interiorly disposed stiffening rings as shown at 12'.

A gas phase or evaporation connection 13 is provided leading from a convenient external point, such as one adjacent one side of the car frame 20, through the space intervening between vessels 11 and 12, to a suitable point at the top of the inner vessel 11. To this end, the connection 13 is shown continuing through a bend at 14 in the intervening space to an inlet T-member 15, the latter having a protected inner end and a branch 14' leading to another connection (not shown), similar to that at 13, on the other side of the car.

A liquid phase connection 16, adapted to serve both as a filling and a withdrawal connection, is provided, and leads from a suitable point near the bottom of the inner vessel through the intervening space to a point without the vessel 12. This connection may also be provided in duplicate. In such case, the two connections pass in opposite directions through the wall of vessel 12 to the exterior. The points in the wall of vessel 12 where both the connections 13 and 16 pass are provided with hermetical sealing means, which conduct relatively little heat from the wall of the vessel 12 to the connections. To this end, the sealing means, as shown at 17, preferably consists of a conical wall made of a material having a

relatively low thermal conductivity and proportioned so that its generating element is of relatively great length whereby the thermal resistance interposed is relatively great. The regulation of 5 the flow of liquid to and from the vessel 11 through the connection 16 is accomplished by means of an interiorly disposed valved controlling means 18 that has a multi-way header 19 attached and with which the connection 16 communicates, the 10 communication being preferably through a bend located in the intervening space, in order to accommodate expansion and contraction in the parts.

In order that liquid withdrawal may be effected 15 in the event of a failure of the valve at 18 to be opened, an auxiliary withdrawal connection 16' is provided, leading from a point within the inner vessel 11 near the bottom thereof, passing upwardly through the top, and thence through a 20 bend in the intervening space to one of the passages in header 19. This connection is constructed like a siphon. To operate this connection, however, a pressure must be generated in 25 the gas space of the inner vessel to lift the liquid past the knee. As long as such pressure exists, such flow will continue. Otherwise, the flow will cease since it is known that a boiling liquid 30 cannot be siphoned; the liquefied gas here transferred being essentially a boiling liquid since its boiling point is below 273° K.

The filling of the inner vessel is also accomplished under pressure from a source of the liquefied gas. When the source is connected through the liquid connection 16, the valve at 18 is opened 35 and liquid enters. To ascertain when the vessel 11 is properly filled, it is provided with one or more trycock connections, as shown at 16'', the outer end of which is passed through the wall of the vessel 12 and provided with a trycock, as 40 shown at 18'.

In tank cars provided in accordance with the invention, the inner and outer vessels are, of course, cylindrically shaped, and the frame 10 which supports the same may be a simple narrow structure made of one or more plate members with an open or cut-away central portion shaped to permit the horizontal passage of the outer cylindrical vessel through the same. Such plate members are preferably provided with stiffening webs adjacent their edges. The frames, which are generally two in number, are then placed along the outer vessel at advantageous points, for example, the "quarter points" or those one-quarter of the length from the ends.

An advantageous form of frame structure for this purpose is shown in Fig. 4 and comprises a pair of parallel substantially rectangular plates 10a and 10b united at the edges by stiffening webs 10c, the plates having circular openings of diameters admitting the vessel 12 snugly and to which it is preferably rigidly secured, for example, by welding. The frame 10 is disposed at right angles to the longitudinal axis of the containers and mounted on car frame 20 (see Fig. 2). The car frame is shown as consisting of a center sill 20c and two side sills 21 and 21' which are joined together in any known manner. To permit the frame 10 to be mounted on the car frame at desired points, other than over the trucks, bolsters, in addition to the conventional truck bolsters, such as shown at 20x, are provided. As shown these additional bolsters consist of two members 22 and 22', which are embodied in the car frame. Such an additional bolster in an end of the car frame may with advantage be located nearer the

center than the conventional bolster and is hence located a desired distance away from the truck bolster toward the center. Each frame 10 is then made fast to the car frame directly over its additional bolster. The car frame is preferably 5 strengthened in addition by suitable means, for example, by the introduction of a strengthening plate 23 that is inserted between the additional bolster and the frame 10, and arranged to overlie and be made fast to the whole of an end portion 10 of the car frame.

The inner vessel 11 is supported directly from the frame 10 and not from the surface of walls of vessel 12, this being accomplished by means of a sling-like arrangement comprising a pair of 15 brackets or lugs 24 made fast to the ends of a girth member 25 disposed about the bottom wall of the inner vessel substantially in the region of the frame 10. Attached to each bracket is a sustaining rod or cable 26 which extends generally 20 upwardly and outwardly and is secured at the upper end to the frame 10. To this end, a collar 27 is made fast in the top web 10c of frame 10, for example, by depositing a fillet of welding metal 10d. Each rod 26 is threaded at its upper end 25 and passed through the collar 27 and provided with one or more nuts 26' arranged to bear on the collar 27.

In order to pass the rods 26 through the wall of vessel 12 in a gas-tight manner, openings are provided in the wall in the region where the rod passes and a sleeve 28 disposed about each rod 26 and attached to the wall 12 in a gas-tight manner, as by welding, the other end of the sleeve being 35 engaged with and made fast to the lower end of collar 27 which is preferably reduced for the reception of the sleeve, the joint being sealed by welding or brazing. The joint between collar and nuts is also made gas-tight while at the same time preserving the adjustability of nuts 26' by the 40 provision of a cap or housing 29 over the nuts 26', the latter being soft soldered in position on the collar 27.

In order that the outer vessel 12 may be braced 45 against end thrusts and otherwise to afford additional support therefor, web members 30 and 30' are interposed between the car frame and the outside wall of the vessel 12 at one or more points, for example, adjacent the additional bolster 22, these members being conveniently formed by taking an I-beam and cutting off the bottom flange and then bending over the web so as to provide an angle-portion that may be bolted to the plate 23 as indicated at 31, the top flange 32 of the I-beam being welded or otherwise arranged to make imperforate engagement with the outer wall of the vessel 12. The inner vessel may be braced by suitable means, for example, by stays, as shown at 36, these being no part of the present invention but are shown and described in copending application, Serial No. 290,971, filed on August 19, 1939, in the name of Zenner, Van Vleet and Hansen.

In Fig. 3, details of the liquid controlling means are shown. Here, a handwheel 150 (see Fig. 1) at the top of vessel 12 has a valve rod 151 which extends downwardly from the handwheel through a packing gland 152 that is hermetically sealed by welding in the top wall in any convenient manner, for example, by means of a dome 153, having a depending flange that fits into a groove in a 70 collar 154, the latter being snugly fitted into and sealed in an opening in the top wall of vessel 12. A housing for the gland 152 is provided in the form of an expandible bellows 155 which extends downwardly and is similarly hermetically sealed 75

in the wall of vessel 11. The valve rod 151 is preferably arranged to make sliding engagement with the valve moving stem 156. To this end, the stem has a sleeve 157, pinned or otherwise secured thereto as shown at 158, the sleeve having a follower 159 brazed to its upper end and adapted to receive slidingly the lower end of the valve rod which may be squared in order to engage therewith and transmit valve moving torque. The valve proper is in a casing 161 which has openings 162 to permit the passage of liquid and has a nipple 163 in threaded engagement with its lower end. This nipple has a flange 164 depending into and made fast to the header 19. To exclude any solid particles in the liquid from entering the valve casing, a screen 165 is placed about the casing 161 over the openings 162. The nipple, thus provided, is brazed into an opening that is provided as indicated in the lower wall of the vessel 11. By such means, it will be understood that the passage of liquid to and from the connection 16 may be controlled, the invention of such means being no part of the present invention, the same being disclosed in copending application, Serial No. 290,972, filed on August 19, 1939, in the name of Hansen and Van Vleet.

In order to insulate properly the contents of the inner vessel from heat that may be transferred from without the outer vessel to the inner vessel by the usual processes of convection, conduction, and radiation, the space between the inner and outer vessels is filled with a substantially dry heat insulating material in a fibrous or comminuted condition. Any suitable material of the character indicated may be employed, for example, asbestos fiber, powdered magnesium carbonate, magnesia cement consisting of magnesium carbonate and asbestos fiber, a finely divided silica material, a glass wool, or a combination of two or more of the same.

In order to permit convenient filling of the space between the inner and outer vessels, one or more manholes are provided in the wall of the outer vessels, such as shown generally at 35 in Fig. 1. This manhole has a cover which makes a gas-tight joint and is sealed in place by soldering.

When the tank car thus constructed has the insulating space properly filled with insulating material in the manner indicated, the insulating effect may be enhanced by the use of a suitable vacuum, as taught in copending application, Serial No. 307,945, filed on December 7, 1939, in the name of L. I. Dana. Such vacuum may be pulled by convenient means, such as a mechanical vacuum pump when connected to the intervening space through a connection (not shown) provided for the purpose in the wall of vessel 12. It is desirable usually that the vacuum so pulled shall be of an order of 0.1 mm. of mercury. Such vacuum pulling means may be either temporarily connected or permanently connected. In the latter case, such means would be mounted at some suitable point on the car frame. In the present instance, a temporary connection is contemplated and the pump disconnected and the connection closed when the desired degree of vacuum obtains in the insulating space.

In operation, the tank car of the present invention is filled by connecting the connection 16 to a source of supply of the liquefied gas, the liquid being forced through the connection, until a desired charge has been introduced, which may be ascertained by opening trycock 18, controlling connection 16", and noting when liquid begins to issue therefrom. At this time, the valve in casing

161 is seated by turning handwheel 150. Material in the gas phase in the vessel 11, displaced during a filling operation, is readily vented through connection 13, which venting may be to the atmosphere, or to a gas receiver, if such be connected at the filling plant to connection 13. During transit, the space in vessel 11 has free communication to the atmosphere through connection 13.

When the car has reached a place of use, the connection 16 is connected to a consumer's receiving device or system (not shown) and the control means at 18 (or the valve in casing 161) opened to permit the withdrawal of liquid. This is accomplished by turning handwheel 150 at the top of vessel 12 to unseat the valve, this handwheel actuating the valve member through rod 151. When a desired quantity has been discharged, the control means is closed.

By this arrangement an accumulation of pressure within the inner vessel is at all times avoided and protection afforded to the control means, whereby loss of liquid from the vessel 11 is avoided even in the event of injury to the connection 16.

Since certain changes may be made in the above construction and different embodiments of the invention could be made without departing from the scope thereof, it is intended that all matter contained in the above description or shown in the accompanying drawings shall be interpreted as illustrative and not in a limiting sense. 30

Having described my invention, what I claim as new and desire to secure by Letters Patent is:

1. In a double-walled tank car construction, the combination with an inner cylindrical vessel adapted for holding a liquefied gas, of an outer cylindrical vessel disposed about and spaced from said inner cylindrical vessel thereby providing an intervening space for insulating purposes, a car frame having a center sill and provided with a bolster, a second frame for supporting said vessels disposed in supporting relation over said bolster and provided with means for supporting the wall of said outer vessel, suspension means for separately supporting said inner vessel from said second frame passed through the wall of said outer vessel, and sealing means joining said suspension means with the wall of said outer vessel. 40

2. In a double-walled tank car construction, the combination with an inner cylindrical vessel adapted for holding a liquefied gas, of an outer cylindrical vessel disposed about and spaced from said inner cylindrical vessel thereby providing an intervening space for insulating purposes, a car frame having a center sill and provided with a bolster in addition to the conventional truck 55 bolsters, a second frame for supporting said vessels disposed in supporting relation over said additional bolster and provided with means for engaging and supporting the wall of said outer vessel, suspension means for separately supporting 60 said inner vessel from said second frame and passing through the wall of said outer vessel, sealing means joining said suspension means with the wall of said outer vessel, and means for bracing said outer vessel against end thrusts having 65 imperforate attachment to the wall of said outer vessel and secured to said car frame.

3. In a double-walled tank car construction, the combination with an inner cylindrical vessel adapted for holding a liquefied gas, of an outer 70 cylindrical vessel disposed about and spaced from said inner cylindrical vessel thereby providing an intervening space for insulating purposes, a car frame having a center sill and provided with a bolster, a second frame for supporting said vessels 75

comprising a structure having an opening therein of sufficient size to admit said outer cylindrical vessel disposed in supporting relation over said bolster, an anchoring member secured to said 5 second frame and having a sleeve adjoining and hermetically sealed in the wall of said outer vessel, a supporting rod made fast in said anchoring member passing through said sleeve and disposed in supporting engagement with the wall of said 10 inner vessel, and means for hermetically sealing the anchorage of said rod against the passage of air from the outer atmosphere into said sleeve and the space between said vessels.

4. In a double-walled tank car construction, 15 the combination with an inner cylindrical vessel adapted for holding a liquefied gas, of an outer cylindrical vessel disposed about and spaced from said inner cylindrical vessel thereby providing an intervening space for insulating purposes, a car 20 frame comprising a center sill and side sills and a plurality of transverse bolsters, a plurality of second frames for supporting said vessels each comprising a structure having a stiffening member and disposed in supporting relation over one 25 of said bolsters, a pair of anchoring members in each of said second frames each secured in a web portion thereof and disposed adjacent the sides, a sleeve depending from each anchoring means and attached thereto in a gas-tight manner, each 30 sleeve being extended down to and sealed in an opening in the wall of said outer vessel, a girth member disposed about the under side of said inner vessel in the region of a frame and having brackets provided with supporting rods which 35 are arranged to pass through said sleeves and be made fast in said anchoring members, means at the upper ends of each of said rods for adjusting the position of said rods in said anchoring members, and housing means for hermetically sealing 40 said adjusting means and the passage of said rods through said anchoring means against the passage of air from the outer atmosphere.

5. In a double-walled tank car construction, 45 the combination with an inner cylindrical vessel adapted for holding a liquefied gas, of an outer cylindrical vessel disposed about and spaced from said inner cylindrical vessel thereby providing an intervening space for insulating purposes, a car 50 frame comprising a center sill and side sills having at least a pair of transverse bolsters, a pair of second frames for supporting said vessels, each comprising a structure provided with a stiffening member and disposed in supporting relation over one of said bolsters, a pair of anchoring members in each of said second frames, each such member being secured in a web portion of said 55 second frame and disposed adjacent the sides, a sleeve depending from each anchoring means and attached thereto in a gas-tight manner, each sleeve being extended down to and sealed in an opening in the wall of said outer vessel, a girth member disposed about the under side of said inner vessel in the region of a second frame and 60 having brackets provided with supporting rods which are arranged to pass through said sleeves and be made fast in said anchoring members, means at the upper ends of each of said rods for adjusting the position of said rods in said anchoring members, housing means for hermetically sealing 65 said adjusting means and the passage of said rods through said anchoring means against access to the outer atmosphere, and means for bracing the outer vessel against end thrusts arranged to make imperforate engagement with the

wall of said outer vessel and secured to said car frame.

6. In a double-walled tank car construction, the combination with an inner cylindrical vessel adapted for holding a liquefied gas, of an outer 5 cylindrical vessel disposed about and spaced from said inner cylindrical vessel thereby providing an intervening space for insulating purposes, a car frame having a center sill provided with a bolster, a second frame for supporting said vessels 10 disposed in supporting relation over said bolster and provided with means for engaging and supporting the wall of said outer vessel, said second frame consisting of at least one plate having a stiffening web and an opening in which said outer 15 cylindrical vessel is rigidly secured, anchoring means secured in a web portion of said frame, supporting sleeves sealed in the wall of said outer vessel and attached to said anchoring means, a girth member disposed about said inner vessel, 20 brackets at the ends of said girth member, supporting connections extending from said brackets through said sleeves and made fast in said anchoring means, and means for bracing said outer vessel against end thrusts attached to the wall 25 of said outer vessel and secured to said car frame.

7. In a double-walled tank car construction, the combination with an inner cylindrical vessel adapted for holding a liquefied gas, of an outer cylindrical vessel disposed about and spaced from 30 said inner cylindrical vessel thereby providing an intervening space for insulating purposes, a car frame having a center sill and provided with a bolster, a second frame for supporting said vessels disposed in supporting relation over said bolster and provided with means for engaging and rigidly supporting the wall of said outer vessel, 35 said second frame consisting of a pair of substantially rectangular plates having cut-away central portions permitting the snug passage of said outer vessel, a stiffening web uniting said plates at the sides and providing a unitary structure, anchoring means secured in a top web of said second frame, supporting sleeves sealed in the wall of said outer vessel and attached to said 40 anchoring means, a girth member disposed about the bottom wall of said inner vessel, brackets at the ends of said girth member, supporting connections extending from said brackets through said sleeves and made fast in said anchoring 45 means, means for hermetically sealing said connections in said anchoring means, and means for bracing said outer vessel against end thrusts having imperforate attachment to the wall of said outer vessel and secured to said car frame. 50

8. In a double-walled tank car construction, the combination with an inner cylindrical vessel adapted for holding a liquefied gas, of an outer cylindrical vessel disposed about and spaced from said inner cylindrical vessel thereby providing an intervening space for insulating purposes, a car frame having a center sill and provided with a bolster, a second frame for supporting said vessels disposed in supporting relation over said bolster and provided with means for 60 engaging and rigidly supporting the wall of said outer vessel, said second frame consisting of a pair of spaced substantially rectangular plates having their central portions cut away sufficiently to admit passage of said outer vessel, stiffening webs connecting said plates at their edges and providing a substantially unitary frame, anchoring means consisting of a pair of collars rigidly secured in the top web at the two sides of said 65 second frame, each consisting of a perforated 70

5 collar brazed in position in said top web, supporting sleeves sealed in the wall of said outer vessel and attached to said collars, a girth member disposed about the bottom wall of said inner vessel, brackets at the ends of said girth member, supporting rods attached to said brackets and extending through said collars and provided

with nuts for adjustably positioning said rods in said collars, and closed caps soft soldered in position over said nuts to said collars whereby the passage through said collars to said intervening space is hermetically sealed. 5

ODD A. HANSEN.
